UNITED STATES PATENT OFFICE

MARIE COUTEN, BORN DOMINGET, OF VINCENNES, FRANCE

AUTOMATIC FIRE EXTINGUISHER

Application filed August 22, 1928, Serial No. 301,376, and in Belgium October 13, 1927.

The present invention relates to an apparatus which may be mounted in the premises to be protected, and which causes an automatic discharge of water when a fire breaks out and the temperature thus rises to a high point.

The said apparatus comprises a water conduit supplied with various discharge nozzles, which conduit is normally closed by a 10 light diaphragm supported by a valve. The said valve is connected directly or by a lever to a suitable element such as a glass rod similar to a thermometer containing a column of mercury, or a fusible part, which will break 15 at high temperatures, thus opening the valve and breaking the diaphragm, thereby enabling an abundant discharge of water through the said nozzles.

The appended drawings show by way of 20 example, in vertical section, two forms of construction of an apparatus according to the present invention.

In the form of construction shown in Fig. 1, the apparatus comprises a conduit 1 connected to a water pipe; to which conduit is secured a hollow metal ball 2 pierced with a certain number of apertures in which are mounted, preferably by being screwed thereinto, the nozzles 3 for the discharge of water.

According to the present invention, I provide between the water conduit 1 and the ball 2, a thin diaphragm 11 of lead or the like which, in normal operation, is supported by a valve disc 4 whose stem 5 extends freely 35 through an aperture 9 in the said ball and rests upon an element so constructed as to break at high temperatures.

The said element may consist of a mercury-containing glass rod 6 as shown, and for 40 greater safety, I further provide a plate or block of fusible metal 7 which supports the thermometer and is laterally guided in the slots formed in a depending strap or yoke 8 secured to the ball 2. A screw 10 passing 45 through the bottom of the yoke and bearing against the block 7 serves to regulate accurately the position of said block and the parts supported thereby.

The operation is as follows:

Should a fire break out, the temperature

will rise, and the rod 6 will break or the block 7 will melt.

In either case, the valve 4 is released, and will fall. Under the pressure of the water, the diaphragm 11 is broken, and the water 55 will be discharged through the nozzles 3, thus extinguishing the fire at the start.

The said apparatus is of substantial construction and is reliable in operation. It may be small and inconspicuous and will not mar the appearance of the premises to be thus protected.

For installations of larger size, in order that the glass rod 6 may not be subjected normally to excessive stresses due to the pressure of the water upon a large surface, I may place between the said valve and the rod a lever whose long arm is adjacent the said rod. An apparatus of this character is shown in Fig. 2.

In this construction, the valve 4, above which is the diaphragm 11, and which traverses the ball 2, as in the preceding case, is secured to a lever 12 pivoted at 13 to a support and downwardly urged by the weight 14. The said lever is attached by an adjustable connecting member 17 consisting, for example, of a turn-buckle, to the rod 6 which may, for instance, be attached to the ceiling.

To provide for additional safety, the device may be attached by means of fusible members 18 disposed between the cross-pieces 15 and 16.

When the temperature rises, the rod 6, or one of the fusible parts 18, will break, and 85 by the action of the weight 14 the lever 12 will fall, drawing with it the valve 4. In order to insure the breaking of said diaphragm in a reliable manner, I prefer to definitely fasten it at its center to the center 90 of the valve by means of a small nickel or other wire 4'.

Obviously, the invention is not limited to the forms of construction herein described, and the apparatus is susceptible of all suitable modifications in detail according to the use to be made of the same. For instance, the said valve may be controlled by any suitable means adapted to break at a high temperature. I employ the glass rod together 100

with a fusible element in the apparatus herein represented for obtaining a twofold security, but a single one of such devices can be used for this purpose if desired.

5. Further, the water nozzles may be employed in any suitable number, and may have various inclinations, so as to discharge the water in a substantially uniform manner.

The movement of the lever 12, during the 10 operation of the apparatus, may be employed for the control of an indicating apparatus such as a bell operated by electric, pneumatic or like means.

I claim:

15. 1. In an automatic fire-extinguisher, a hollow body having one or more nozzles to discharge liquid therefrom; a conduit attached to said body to supply liquid to its interior; a frangible element clamped between said 20 conduit and body and normally closing communication between them; a valve having a head for sustaining the frangible element against breakage by the pressure of the liquid against it, said frangible element being incapable by itself of withstanding said 25 pressure; and means associated with said valve for normally holding it in active position, said valve-holding means embodying a frangible element other than the one clamped 30 between the conduit and hollow body and which will be ruptured at a predetermined high temperature, and also embodying a fusible body.

2. In an automatic fire-extinguisher, a hollow body having one or more nozzles to discharge liquid therefrom; a conduit attached to said body to supply liquid to its interior; a frangible element clamped between said 40 conduit and body and normally closing communication between them; a valve having a head for sustaining the frangible element against breakage by the pressure of the liquid against it, said frangible element being incapable by itself of withstanding said 45 pressure; and means associated with said valve for normally holding it in active position, said valve-holding means embodying a frangible element other than the one clamped between the conduit and hollow body and also 50 embodying a member which is rendered inoperative on a predetermined increase in temperature.

3. In an automatic fire-extinguisher, a hollow body having one or more nozzles to discharge liquid therefrom; a conduit attached to said body to supply liquid to its interior; a frangible element clamped between said 60 conduit and body and normally closing communication between them; a valve having a head for sustaining the frangible element against breakage by the pressure of the liquid against it, said frangible element being incapable by itself of withstanding said pressure; and means associated with said valve 65 for normally holding it in active position,

said valve-holding means embodying a frangible element other than the one clamped between the conduit and hollow body and also embodying a member which is fusible at a predetermined temperature.

4. An automatic fire-extinguisher according to claim 3, in which the valve-holding means additionally embodies a weighted lever pivoted to the hollow body and to which the valve is pivotally connected, said lever being held against swinging movement under the influence of its weight by the frangible element other than the one which is clamped between the liquid supply conduit and the hollow body.

5. In an automatic fire-extinguisher, a hollow body having one or more nozzles to discharge liquid therefrom; a conduit attached to said body to supply liquid to its interior; a frangible element clamped between said 85 conduit and body and normally closing communication between them; a valve having a head for sustaining the frangible element against breakage by the pressure of the liquid against it, said frangible element being incapable by itself of withstanding said pressure; a member positively fastening the frangible element at its center to the center of the valve head; and means associated with said valve normally tending to move the valve 90 away from the frangible element, said means being capable of being destroyed by heat; whereby on destruction of the said means the valve will separate from the frangible element, thereby breaking the latter and permitting the operation of the valve.

6. An automatic fire-extinguisher according to claim 5, in which the valve-holding means embodies a weighted lever pivoted to the hollow body and to which the valve is pivotally connected, said lever normally tending to move the valve away from the frangible element, said fastening member insuring breakage of the frangible element when said lever swings downward under the influence 105 of its weight.

In testimony whereof I affix my signature.
MARIE COUTEN, BORN DOMINGET.
